Mack & Litzenberg, Attorneys.

UNITED STATES PATENT OFFICE.

ALBERT KATZKE, OF MILWAUKIE, OREGON.

NECKTIE-HOLDER.

1,313,822.

Specification of Letters Patent. Patented Aug. 19, 1919.

Application filed November 4, 1918. Serial No. 262,062.

To all whom it may concern:

Be it known that I, ALBERT KATZKE, a citizen of the United States, residing in the city of Milwaukie, county of Clackamas, 5 and State of Oregon, have invented certain new and useful Improvements in Necktie-Holders, of which the following is a specification.

My invention relates to neck tie holders, 10 and has as its principal object to provide a device to which a neck tie can be tied and which can be attached to the collar and collar button without being untied, thus making it possible to tie a tie on the device 15 and not remove it therefrom until it is desired to substitute another tie therefor, said device being provided with means for yieldingly holding the tied tie up snugly in the collar and so that it will not accidentally 20 work down over the collar button.

I have illustrated one practical embodiment of my invention on the accompanying sheet of drawings which I will now describe.

25 Figure 1 is a front view of my device, a collar and tie being indicated in dotted lines;

Fig. 2 is a rear view of the device without the tie;

Fig. 3 is an edge view thereof, and

30 Fig. 4 is a cross sectional view thereof taken on line 4—4 of Fig. 2.

Referring now more in detail to the drawings, my invention as here embodied, comprises a body member 1, having the wing 35 portions 2, 2, and also having the inturned side portions 3, 3, to form a guide way for a slide holding member 4. Said holding member 4 is turned over at its upper end and formed into a two pronged hook 5, 40 adapted to hook over the collar button B. Said holding member 4 is also provided with a longitudinal slot 6, and with a struck in finger 7. The lower end of the body 1 is turned inwardly and downwardly to form 45 a coöperating finger 8. A rubber band 9, or other elastic member, is connected to the fingers 7 and 8, on the back side of the device and normally moves the holding member downwardly relative to the body member 1. This action tends to force the body 50 member 1 up under the collar C, and the holding member down on the collar button B, thus preventing the tie and the tie holder

from accidentally working down from under the collar. In other words, the tied tie is 55 held yieldingly up in place under the collar. In order to remove the same, it is only necessary to press upwardly on the lower end of the holding member 6, which lifts the hook 5 off the collar button and permits 60 the easy removal of the tie from under the collar. The device as here shown is adapted for the four-in-hand tie, and the lower parts of the body member 1 and the holding member 6 can be inserted into the rear of the 65 tie if desired.

I am aware that changes in the details of my invention as here shown can be made without departing from the spirit thereof, and I do not, therefore, limit my invention 70 except as I may be limited by the hereto appended claims.

I claim:

1. A neck tie holder of the character referred to comprising a body having wing 75 portions at its upper end and having its lower end bent rearwardly, a coöperating member slotted to receive the bent lower end of said body, means holding said body and said coöperating member in sliding engagement with each other, said coöperating member being adapted at its upper end to hook over a collar button, and means normally and yieldingly moving said body and said coöperating member in opposite directions 80 longitudinally of each other, substantially 85 as described.

2. A neck tie holder of the character referred to comprising a body member of substantially Y-shape having the lower end 90 of its stem portion bent rearwardly and having integral guide portions at opposite sides of said stem portion, a coöperating member slidably mounted in said guide portions and being slotted to receive the bent lower end of 95 said stem portion, and means yieldingly moving said body member and said coöperating member in opposite directions relative to each other, substantially as described.

Signed at Milwaukie, Clackamas county, 100 Oregon, this 11th day of September, 1918.

ALBERT KATZKE.

In presence of—

JOHN W. BATES,
JOHN C. HOTZ.
